UNITED STATES PATENT OFFICE.

GEORGE ERNEST WILSON, OF TYNEMOUTH, AND JOSEPH EDWIN TULIP, OF MONKSEATON, ENGLAND.

TIN OPENER.

Application filed December 4, 1920. Serial No. 428,339.

To all whom it may concern:

Be it known that we, GEORGE ERNEST WILSON and JOSEPH EDWIN TULIP, both subjects of the King of Great Britain and Ireland, and residents, respectively, of Tynemouth and Monkseaton, county of Northumberland, England, have invented a certain new and useful Improvement in Tin Openers, of which the following is a specification.

This invention relates to an improved tin opener and provides an instrument which is of simple and cheap construction, easy and safe to manipulate, with a powerful and rapid cutting action, and which is adaptable to beaded tins of all sizes, and can be readily packed with them.

The instrument is of the type which is in one piece stamped out of sheet metal with the cutter blade bent from the handle, but our invention differs from previous tin openers of the said type in providing a projection which serves as a rolling fulcrum for the leverage exerted by the thumb and fingers of the user, and by the particular angle at which the cutter blade is set from the handle, in giving greater freedom for manipulation without the user's hand coming against the tin.

It has been previously proposed to use a tongue immediately under the cutting hook of a tin-opener to slip below the seam of a tin and serve as a pivot for pressing the hook edge through the cover of the tin, and the projection serving as a rolling fulcrum in our invention differs from such a pivot in that it has greater length and leverage extending as it does behind the cutting hook and thereby preserves nearly the same distance between the rolling contact of the said fulcrum and the point at which the cutting blade is being applied to the tin after the first cut has been made.

The length of the projection in our invention may be varied according to whether an instrument making a long or a short cut at each stroke is desired.

According to this invention, the instrument is conveniently made of a metal stamping which has at one end a cutter blade consisting of a pointed hook having a cutting edge extending from the point of the hook to the junction with the handle part of the stamping, as shown, for example in Figure 1 of the accompanying drawings, which

illustrate one form of construction, and is a view of the back of the stamping in the first stage of manufacture. At the junction of the handle *a* with the hook *b* there is shown a gap *c* formed by a projection *d* (Figure 60 3) being bent from the side of the handle where the cutting edge finishes and from the junction the hook is bent along the dotted line (Figure 1) which line is at an acute angle with the handle, into the form shown in Figure 2, which is a view of the back of the instrument after the said bending has been done and which shows the gap *c*.

Figure 3 is a perspective view of the instrument seen from the front. The projection *d* is formed by stamping a portion of the handle *a* into a position at approximately right angles to the handle. The top surface of the projection may be flat, but is preferably curved, and the side has a slight inward curve to enable the cutter to "cling" to the edge of the tin, under the bead.

Figure 4 shows another method of bending the projection *d* from the handle.

Figure 5 shows the tin opener in operation on the edge of a tin having a beaded edge under which the projection *d* fits and acts as a rolling fulcrum for the leverage exerted by the thumb and fingers of the user on the handle, *a*. The thumb is placed on that side of the handle which is opposite the hook and the fingers at the other side of the handle, and the action of pushing with the thumb and pulling with the fingers drives the point of the hook into the tin, cutting the metal and bringing the handle up towards the top of the tin. The handle is then depressed and the projection *d* moved to another position along the edge of the tin 90 where it is in readiness for another cut.

It is to be understood that the angle at which the hook *b* is bent from the handle *a* keeps the said handle obliquely away from the side of the tin and ensures freedom for the fingers in their grip of the handle during the cutting stroke, and that the curved projection *d* serves to keep the speed of the cutting stroke approximately constant by preserving nearly the same distance between the fulcrum and the point at which the cutting blade is applied to the tin, since the rolling fulcrum recedes as the blade advances through the metal after the first cut has been made. It is also to be understood 110

that this rolling fulcrum enables a longer cut to be made at each stroke than can be achieved by previous tin openers of the type referred to.

5 Figure 6 shows in perspective a modified form of construction, the hook *b* and projection *d* being placed at the lower end of the handle *a* and bent at approximately 90 degrees therefrom in opposite directions, 10 which arrangement allows full advantage of the leverage and keeps the fingers and thumb of the operator's hand above the tin.

Figure 7 is a side view of Figure 6; and Figure 8 is a plan view of Figure 7.

15 Figure 9 shows the modified tin opener cutting a tin. In this case the instrument is held upright, the point of the hook being on the top of the tin against the inner side of the rim, and the projection *d* being held 20 against the underside of the outer rim. The grip thus secured is maintained by endeavouring to twist the instrument to the right. A forward and downward pressure of the instrument causes the point of the hook to 25 pierce the top of the tin easily, and to cut the metal for the whole length of the blade, the projection *d* meanwhile rolling along

the underside of the outer rim. At the end of the cut the instrument is brought towards the user and into the upright position, and 30 the action is repeated as before all round the rim of the tin.

We claim:—

1. A can opening tool including a body having a cutting blade offset from the body 35 at right angles thereto, and a fulcruming foot spaced from the junction of the blade with the body to provide a clearance recess and offset from the body oppositely to the blade thereby to have a bearing engagement 40 with the side of the can.

2. A can opening tool including a body having a cutting blade and a fulcruming foot offset from one edge thereof in opposite directions and at right angles to the plane of 45 the body, the said fulcruming foot being curved to engage the rounded side of a can and spaced from the point of junction from the blade with the body to provide a recess.

In testimony whereof we have hereunto 50 set our hands this tenth day of November 1920.

GEORGE ERNEST WILSON.
JOSEPH EDWIN TULIP.
